UNITED STATES PATENT OFFICE.

WILLIAM F. MARKHAM, OF PLYMOUTH, MICHIGAN.

AIR-GUN.

SPECIFICATION forming part of Letters Patent No. 655,170, dated July 31, 1900.

Application filed December 18, 1899. Serial No. 740,672. (No model.)

To all whom it may concern:

Be it known that I, WILLIAM F. MARKHAM, a citizen of the United States, residing at Plymouth, in the county of Wayne and State 5 of Michigan, have invented certain new and useful Improvements in Air-Guns, of which the following is a specification, reference being had therein to the accompanying drawings.

The invention relates to air-guns of the 10 type commonly known as "breakdown" guns, and has particular reference to the novel means employed for connecting the barrel with the stock to permit the breaking to be effected.

15 The invention consists in the novel construction of a connecting device of this character and in the peculiar manner in which it is combined with the gun barrel and stock, as will be more fully hereinafter shown and 20 described.

In the drawings, Figure 1 is a side elevation of an air-gun embodying my invention. Fig. 2 is a detached perspective view of the 25 connecting device. Fig. 3 is a plan view of the blank from which the connecting device is formed; and Fig. 4 is a section taken on line $x-x$, Fig. 2.

In the drawings thus briefly referred to the letter A represents the stock of the gun, which 30 is provided with a housing B, adapted to receive and to have pivotally connected therein the connecting device, hereinafter described.

C designates the gun-barrel, which extends 35 forwardly of the stock in the usual manner, the usual piston and springs contained in the barrel not being shown, as they form no part of the present invention.

D designates the connecting device, which, 40 as stated, has a pivotal connection with the stock A and extends beneath the barrel C, forming the support for the latter. This connection referred to is so formed as to constitute a housing for the trigger, a forearm for 45 the gun-barrel, and a fulcrum-arm which is connected to the stock by means of a pivot-pin a . The connecting device, which is and 50 will be hereinafter referred to as a "housing" is preferably formed from a single sheet-metal blank E, having preferably a squared end F and a tapering end G. The blank is aper-

tured at substantially its center, as shown at H, and I I' I² designate lips projecting into the aperture.

J' is a recess formed in the marginal portion J of the blank about the aperture.

In the formation of the housing the blank is cut along the lines b and c and bent upwardly along the lines d and e, forming the housing-bottom K and side walls L, as plainly 60 shown in Fig. 2. The blank is then bent at right angles to the sides along the lines g and h, one marginal portion being folded over the other, as shown in the figure last referred to, to form the housing-top M. The portions i i' 65 are bent along the lines j j' and are curved, as shown in Fig. 2, to form bearing-flanges A² for the inner end of the barrel.

The marginal portion J when the blank has been folded in the manner set forth is 70 bent at right angles to the plane of the sides, forming flanges l. The lips I I' I² are also bent into engagement with each other, as shown in Fig. 2, the aperture and the marginal portions forming, respectively, a recess 75 A³ in the under side of the housing and a slotted cover for the recess, through which the trigger A⁴ is adapted to extend. One end of the housing thus described is apertured, as at a², and is adapted to extend within the 80 metallic housing B, as shown in Fig. 1, the parts being connected by the pivot-pin referred to. The opposite end of the housing has the beveled or inclined end, the bevel extending from the housing B forward and beneath the gun-barrel constituting the forearm. The barrel is secured to the flanges 85 A² of the connecting device in any suitable manner, as by brazing. It will be observed that the connecting device thus formed is 90 composed of two separated vertical side plates tied together and braced apart by the bottom and top members K and M; also, that the forward end of said device is provided with inclined flanges A², to which the gun-barrel is 95 connected. As a result of this peculiar construction the strain caused by the "breaking" down of the gun is applied across the vertical side plates and the danger of breakage of parts is obviated. Furthermore, by turning 100 in the flanges l around the trigger-guard recess the side members are further strength-

ened and stiffened against "buckling" or bending.

The device is best made of a single piece struck by dies, as herein described, as it 5 avoids rivets and simplifies and cheapens the device. It is obvious, however, that it may be made in other ways without departing from the spirit of my invention.

What I claim as my invention is—

- 10 1. A connection between an air-gun barrel and stock, comprising two separated vertical side plates, tie-plates separating and tying the side plates together, flanges at the forward edges of the side plates to which the barrel is connected, and a pivotal connection between the rear ends of the side plates and the stock.
- 15 2. A hollow connecting member between an air-gun barrel and stock, comprising two separated, vertical, metallic side plates, each having a trigger-recess formed therein, a bottom connecting member, a top connecting member extending along the rear portions of the vertical plates, and side flanges at the forward edges of said latter plates to which the barrel is connected.
- 20 3. A member for connecting the barrel and stock of an air-gun, formed of a single piece of sheet metal, comprising side plates, a con-

necting bottom member, a connecting top 30 member extending along the rear portions of the side plates, outwardly-projecting flanges at the forward top portions of said side plates to which the barrel is secured, a trigger-recess being formed in the under side of the 35 side plates, and an inturned flange at the edge of each recess for the purpose described.

4. In an air-gun, a connecting device for the gun barrel and stock, comprising two separated metallic side plates, the outer end 40 portions thereof being beveled forming inclined forward edges, and the lower portion of each plate being recessed, a bottom tie-plate connecting the lower edges of the side plates, a top tie-plate for the side members 45 extending along their upper edges from the inner ends of the side plates to their inclined forward edges, an outwardly-projecting flange upon the inclined forward edge of each side plate, and an inturned flange at the edge of 50 each recess formed in the side plates.

In testimony whereof I affix my signature in presence of two witnesses.

WILLIAM F. MARKHAM.
